WIDE ANGLE TELESCOPIC SIGHT

John F. Thompson and Donald R. Payton, El Paso, Tex.,
assignors to W. R. Weaver Company

Continuation-in-part of design application Ser. No. 378,737, July 12, 1973, which is a continuation-in-part of abandoned design application Ser. No. 255,933, May 22, 1972. This application Apr. 3, 1974, Ser. No. 457,525

Term of patent 14 years

Int. Cl. D16—06

U.S. Cl. D57—1 E

FIG. 1 is a top plan of a wide angle telescopic sight embodying our new design;

FIG. 2 is a side elevational view taken from the right side of the sight as seen with respect to FIG. 1;

FIG. 3 is a bottom plan view of the sight of FIG. 1;

FIG. 4 is a side elevational view taken from the right side of the sight as seen with respect to FIG. 3;

FIG. 5 is an elevational view taken looking at the ocular end of the sight; and

FIG. 6 is an elevational view taken looking at the objective end of the sight.

The new design is characterized by the ocular lens housing being laterally enlarged and provided with upper and lower smooth curved surfaces which intersect side smooth surfaces and a forward conical surface along sharp lines, as shown in FIGS. 1, 3 and 5; and an ocular lens retainer having upper, lower and side surfaces of constant thickness as shown in FIG. 5.

This application is a continuation-in-part of design

application Ser. No. D. 378,737, filed July 12, 1973, which in turn is a continuation-in-part of design application Ser. No. D. 255,933, filed May 22, 1972, and now abandoned.

We claim:

The ornamental design for a wide angle telescopic sight, as shown and described.
